MACHINE FOR ROUTING STAIR STRINGERS

Olaf Pearson, West Orange, N. J.

Application May 3, 1954, Serial No. 427,187

12 Claims. (Cl. 144—136)

This invention relates to a machine for making stair stringers. More especially, the invention is concerned with the routing of channels in the face of a stair stringer for receiving the ends of the risers and the treads of a stairway.

It is an object of the invention to provide an improved machine for making stair stringers, and the improvements are concerned more especially with adjustments whereby the machine can be used for making stringers for staircases having a wide variety of rise-to-run ratios. Staircases are not standardized, and the architect for each house makes his own selections for the height of each step and the depth of the tread of the step. Depending upon these factors and the height of the ceiling in the house, the number of steps and the rise-run ratio are determined. With this invention, it is possible to cut stringer channels for any selected rise-run ratio that may be called for by the plans of any house.

This invention relates to machines of the class in which the stair stringer is located under a guide plate having slots through which a router tool extends, and in which the sides of the slots serve as guides for the router tool.

In accordance with one feature of the invention, the mechanism for feeding the stair stringer, with a step-by-step motion, is provided with an adjustment for correlating the length of the feed steps with the rise-run ratio for which the router guides are set. Another feature of the invention relates to the control means for operating the feed mechanism and for operating clamps that hold the stair stringer accurately in position during each routing operation. This control mechanism is constructed for sequential operation so that the feed mechanism and clamping means will operate in the desired relation to one another. Other features relate to a construction for cutting the channels for right and left-hand stringers, for reversing the operation of the feeding mechanism, and for automatically selecting different clamping means depending upon whether the machine is adjusted for cutting a right or a left-hand stringer.

Other objects, features and advantages of the invention will appear or be pointed out as the description proceeds.

In the drawing, forming a part hereof, in which like reference characters indicate corresponding parts in all the views:

Figure 1 is a front elevation of a machine for routing stair stringers in accordance with this invention;

Figure 1a is a greatly enlarged sectional view through the rack and its support of Fig. 1, the section being taken at the plane 1a—1a indicated in Figure 1;

Figure 2 is an enlarged sectional view taken on the line 2—2 of Figure 1;

Figure 3 is a detailed view of a portion of the mechanism for feeding the holder on which the stair stringer is carried;

Figure 4 is a top view of the feeder mechanism shown in Figure 2;

2

Figure 5 is an enlarged, top plan view of the stringer routing machine shown in Figure 1;

Figure 6 is a top plan view of one end of the stringer holder viewed from the plane 6—6 of Figure 1;

Figure 7 is an enlarged sectional view taken on the line 7—7 of Figure 5;

Figure 8 is an enlarged end view of the stringer routing machine shown in Figures 1 and 5;

Figure 9 is a greatly enlarged front view of the manually controlled device for controlling the sequence of operations of the machine;

Figure 10 is a sectional view through one of the guide plates showing the way in which a router tool is guided by the edge of the slot through the guide plate;

Figure 11 is a diagrammatic view showing the fluid motor by which the feed mechanism is operated and the magnetic valve by which the working fluid supply to the motor is controlled; and

Figure 12 is a wiring diagram for the machine shown in the other figures.

The machine shown in Figure 1 includes a main frame 10 with supporting legs 11 which rest upon the floor. The top of the main frame 10 includes longitudinal channels 12, best shown in Figures 5 and 8; and transverse tie-plates 13. The space enclosed by the channels 12 and tieplates 13 is open to leave room for router tools to reach the work piece.

On top of the channels 12 and tieplates 13 there are guide plates 16 and 17. These guide plates have slots 21 and 22 through which the cutting tool extends. There are graduations along one side of each of the slots 21 and 22 and these sides of the slots serve as guide means for router tools that cut the grooves in the stair stringers. The edge of the slot 21 guides the tool for cutting the groove in the stringer for the tread of the stair, and the slot 22 guides the tool for cutting the groove in the stringer which receives the riser.

The guide plate 16 is used for cutting right-hand stringers and the guide plate 17 is used for cutting left-hand stringers. It will be evident, therefore, that for any particular work piece, only one of the guide plates is used to guide the tool. It is an important advantage of the invention, however, that means are provided for simultaneously adjusting the guide plates 16 and 17 for different values and combinations of rise and run distance so that after putting one stair stringer through the machine, the machine is accurately adjusted to cut the corresponding stringer for the other side with exactly corresponding dimensions.

The guide plates 16 and 17 have slots 25 through which stud bolts 26 extend. These stud bolts are attached to the longitudinal channels 12 and they have nuts 27 at their upper ends for securely clamping the guide plates 16 and 17 to the longitudinal channels 12. When the guide plates 16 and 17 are to be adjusted to make stair stringers with a different rise or run from those of the last stringer made on the machine, the nuts 27 are loosened so as to leave the guide plates 16 and 17 free to move on the top faces of the channels 12. The slots 25 are arcuate slots with centers of curvature at axes 29. The guide plate 16 is provided with a bearing on which it rotates about one of the axes 29 as a center. This construction is shown in Figure 7.

A bearing element 30 is attached to the underside of the plate 16 by screws 31. The bearing element 30 is arcuate with its center of curvature at the axis 29, and while the bearing element extends for more than 180° of arc, it does not cross the slots 21 and 22. In the construction illustrated, the ends of the bearing element 30 are at the guide surfaces of the slots 21 and 22. The bearing element 30 could be shorter, but it is preferably greater than 180° in order to provide a more adequate bearing.

The bearing element 30 has an undercut recess 33

around its outer portion, and there is a connecting plate 35 with an inner lip which fits the undercut recess 33. The connecting plate 35 is secured to the forward channel 12 of the main frame. The bearing surfaces of the undercut recess 33 and the complementary lip of the connecting plate 35 provide the bearing means on which the plate 16 is movable angularly about the axes 29 as a center.

Referring again to Figure 5, the guide plates 16 and 17 are connected together by a block 40 which has screws 42, or similar fastening means, connecting it with the respective guide plates. A lead screw 44 threads through the block 40; and the forward portion of the lead screw rotates in a thrust bearing 45 which prevents longitudinal movement of the lead screw. When a wrench or handle is applied to the forward end of the lead screw 44 and the lead screw is rotated, the block 40 is moved toward or away from the thrust bearing 46, depending upon the direction of rotation of the screw.

As the lead screw 44 is turned in a direction to pull the block 40 toward the thrust bearing 45, the plate 16 is rotated clockwise about its axis 29, and the plate 17 is rotated counter-clockwise about its axis 29. This movement in opposite directions effects the same adjustment for the guide slots in both of the plates 16 and 17 because the guide slots are turned in opposite directions to compensate for the fact that one operates on a right-hand stringer and the other on a left-hand stringer. There are scales 46 along outer arcuate edges of the plates 16 and 17 and these scales 46 move past indicators 47 on the main frame of the machine. This enables the operator of the machine to tell when the plates have been brought to a pre-selected adjustment. After the desired adjustment has been reached, the nuts 27 are tightened and the plates 16 and 17 are securely held in the position at which they have been set.

A stringer carrier 50 extends through the main frame 10 and projects beyond both ends of the main frame. This stringer carrier 50 is a long beam, and preferably a channel beam, so as to increase its rigidity. The stringer or work piece 52 rests upon the stringer carrier 50. There is a stringer holder 54 (Figure 1) including a clamp 56 for gripping the end of a stringer. The stringer holder 54 has a handle 57 which operates the clamp 56. The stringer holder 54 is carried by a slide 60 which extends lengthwise of the stringer holder 54.

Referring to Figure 2, there are grooves 62 in the confronting top edges of the sides of the stringer holder 54 and these grooves provide a track along which the slide 60 is movable to feed the stringer 52 through the machine. On the bottom face of the slide 60 there is a rack 64.

Referring again to Figure 1, the rack 64 meshes with the teeth of a pinion 66 when the slide 60 is to be moved toward the right and meshes with another pinion 67 when the slide is to be moved toward the left. The mechanism for selectively engaging the pinion 66 or 67 with the rack 64 will be described in connection with Figure 4.

The pinion 66 always meshes with the pinion 67 and transmits rotary motion to the pinion 67. The pinion 66 is driven by a gear 68 (Figure 3) on a shaft 70. A ratchet wheel 72 is secured to the shaft 70 and is rotated by pawls 74 carried by a driving pinion 75 which is also located on the shaft 70 but freely rotatable on the shaft.

The pawls 74 are connected with the pinion 75 by studs on which the pawls are free to swing in the usual manner, and all of the pawls have a bias toward the ratchet wheel 72. The studs on which the pawls swing are located so that when one pawl is in engagement with the back of a tooth of the ratchet wheel, each successive pawl around the ratchet wheel is progressively further from the back of the corresponding ratchet tooth in front of that pawl. With this construction, there can be very little angular movement of the pinion 75 with respect to the ratchet wheel 72 without bringing one or another of the pawls 74 into position to contact with the back of one or the other of the teeth of the ratchet wheel 72. The

pawl and ratchet mechanism illustrated, therefore, puts a minimum of lost motion into the driving mechanism of the machine.

Referring again to Figure 1, the pinion 75 meshes with a rack 78 extending from a piston rod 79 of a fluid-actuated motor 80. This motor 80 is secured to the front of the main frame 10 and has a bearing 82 in which the piston rod reciprocates.

When the piston rod 79 moves toward the left in Figure 1, the pinion 75 is rotated counter-clockwise, and the shaft 70 is rotated in the same direction through the pawl and ratchet mechanism on the shaft 70. When the piston rod 79 moves toward the right, on its return stroke, the pinion 75 moves clockwise, but no rotation is imparted to the shaft 70 because the pawls of the ratchet mechanism move across the sloping faces of the ratchet teeth without turning the ratchet wheel.

There is a slideway 84 fixed to the main frame and having an undercut groove 85 (Figure 1a) by which the rack 78 is supported and in which the rack is freely slideable in the direction of its length. There is a scale 86 which is also connected to the frame to indicate the stroke of the motor 80 and rack 78. A lead screw 88 threads through a block 90 on the front of the frame and carries an abutment 92 for limiting the stroke of the motor 80 and rack 78. The rack 78 contacts with the abutment 92 at the end of the stroke.

By changing the setting of the lead screw 88, the abutment 92 can be shifted to any desired position along the scale 86 so as to obtain any pre-selected stroke for the motor 80 and rack 78.

The successive operations of the motor 80 move the stringer holder 54 with a step-by-step movement, and the correct length for each step depends upon the correct rise for the stair stringer which is to be routed by the machine. The proper settings for the abutment 92, as well as the angular adjustment of the guide plates 16 and 17, are taken from a table which shows different values and combinations of rise and run with increments small enough to obtain any desired stair case.

There are stringer holders 54 at both ends of the stringer carrier 50. When the stringer is to be advanced through the machine toward the right, the end of the stringer is placed in the clamp of the left-hand stringer holder 54; and when the stringer is to be advanced through the machine toward the left, the rearward end of the stringer is placed in the clamp 56 of the right-hand stringer holder 54. Mechanism for reversing the direction of travel of the slide 60, which moves the stringer holders 54, is best shown in Figure 4. The gears 66 and 67 rotate freely on shafts 96 and 97 and are held against axial movement on these shafts by thrust collars 98. The shafts 96 and 97 themselves are axially movable in bearings 99 carried by the main frame. When the gears 66 and 67 are in the positions shown in Figure 4, the gear 66 meshes with the rack 64, but the gear 67 is beyond the side of the rack. When the shaft 96 is moved rearwardly, to carry the gear 66 into the dotted line position shown in Figure 4, the gear 66 remains in mesh with the driving gear 68, but moves beyond the side of the rack 64 and out of mesh with the teeth of the rack. At the same time that the gear 66 is moved rearwardly, the gear 67 is moved forward into the dotted line position shown in Figure 4, and in this position it meshes with the rack 64.

This movement of the gears 66 and 67 is effected by a yoke element 101 which rocks about a vertical stud 102, and which has pins 103 engaging circumferential grooves in the shafts 96 and 97. There is a handle 105 extending forwardly into position to be actuated by the operator of the machine whenever the direction of movement of the stringer holders is to be reversed.

The routing of the stringers is done by routing tools 108 (Figure 1) mounted on top of the guide plates 16.

and 17. Each of these router tools 108 includes a motor 110 which has a housing with a bottom flange 112 that rests upon the guide plate 16 or 17. The bottom face of the flange 112 provides a bearing surface that slides on the top surface of the guide plate. There are handles 115 on both sides of the router tool 108 for moving it along the guiding edges of the slots in the guide plates.

Figure 10 illustrates the way in which each of the router tools 108 is guided to route one of the stringers 52. A cutter wheel 118 is attached to the lower end of the armature shaft of the motor 110. Between the cutter wheel 118 and the bottom face of the flange 112, there is a guide roller 120 which contacts with the edge of the slot 22 to guide the cutter wheel 118 along a straight line. The router tool 108 is moved in one direction along the slot 22 with manual pressure exerted in a direction to hold the guide roller 120 against one side of the slot 22. After cutting to the end of the slot 22, the router tool 108 is moved in the opposite direction with manual pressure exerted to hold the guide roller 120 against the other side of the slot 22 so that the recess routed in the stringer has the same width as the guide slot 22, less the difference in diameter of parts 118 and 120.

In order to hold the stringer against movement while it is being routed, clamps are provided in the machine. The clamps are best shown in Figures 8. There is a clamping plate 125 located under the stringer 52 in the region of each of the connecting plates 35 which support the bearing means on which the guide plates are angularly adjustable. There is a spacer 132 on the bottom of the guide plate 17 which has a bottom face flush with the bottom face of the connecting plate 35.

The clamping plate 125 is connected to a piston rod 127 of a fluid motor 128. The rearward end of the clamping plate 125 is supported by studs 129 which extend downwardly from the guide plate 17 and through holes in the clamping plate which are large enough to make the clamping plate 125 freely movable along the studs 129.

The motor 128 is supported on a cross brace 130 of the main frame of the machine. When working fluid is supplied to the motor 128, the clamping plate 125, is pushed upwardly and this lifts the stringer 52 from the stringer carrier, and clamps the stringer firmly against the bottom faces of the connecting plate 35 and spacer 132. By so clamping the stringer after each advancing step, a uniform depth of the routed grooves is obtained.

A clamping jaw 135 is located above each of the clamping plates 125, and this clamping jaw 135 is connected to a piston rod 137 of a fluid-operated motor 138 which is secured to the main frame of the machine. When working fluid is supplied to the motor 138, to thrust the piston rod 137 toward the left in Figure 8, the clamping jaw 135 pushes the stringer against an abutment 140 at the front of the machine. This abutment is adjustable, within a limited range, toward and from the front frame channel 12, by lead screws 142 located near opposite ends of the abutment 140, as shown in Figure 5. In order to keep the abutment 140 in parallel positions when it is adjusted by the screws 142, these screws have sprockets 143 (Figure 1) connected to them, and the sprockets 143 are connected together by a chain 150 so that the sprockets are rotated in unison.

Referring again to Figure 8, there are one or more nozzles 155 located at the abutment 140 and facing in the direction of the stringer 52. When each routing operation has been performed on the stringer and the clamping plate 125 moves downwardly, to leave the stringer free for its next step of advance, jets of compressed air are blown across the top surface of the stringer from the nozzles 155 to remove all particles of wood which spill onto the top surface of the stringer from the routed grooves or from the cutter wheels. This clearing of wood shavings from the top face of the stringer prevents

the stringer from being held out of contact with the bottom faces of the plate 135 and spacer 132 when the plate 125 again moves upwardly into clamping position. Valves 156 control the air jets.

The sequence of operation of the machine is controlled by a crank 160 located at the front of a master control switch 162. This crank is movable into five different positions indicated by the letters A, B, C, D and E (Figure 9) on the front of the switch housing. All of the valves for controlling the fluid-operated motors of the machine are preferably operated by solenoids, and are so illustrated in the drawing, though the invention can be made with mechanically operated valves.

Figures 11 and 12 are diagrammatic views showing the control apparatus for the machine. Figure 11 shows slide valve 166, for controlling the flow of working fluid to the motor 80. The slide valve 166 includes a casing 170 containing a valve element 172. There is a port in the valve casing 170 communicating with a conduit 172 which supplies air under pressure to the valve casing. There are two exhaust ports 174 opening through the valve casing 170 at spaced locations lengthwise of the valve casing. There is another port connected with a conduit 175 which leads to the crank end of the motor 80; and another port communicating with a conduit 176 which leads to the head end of the cylinder 80.

The valve element 172 is urged toward the right in Figure 11 by a spring 180. A magnetic stem 182, of the valve element 172, extends into a solenoid coil 184.

30 The spring 180 urges the end of the valve 170 against an abutment 186 near one end of the valve casing. When the valve element 172 is against the abutment 186, the circumferential groove in the valve element puts the conduit 175 in communication with the pressure conduit 172 so that compressed air is supplied to the crank end of the motor 80 to operate the piston toward the right; and the conduit 176 is in communication with the exhaust port 174.

When the solenoid 184 is energized, it moves the stem 40 182 and the valve element 172 toward the left, against the pressure of the spring 180 and into the position shown in Figure 11. This puts the the conduit 176 in communication with the pressure conduit 172; and connects the conduit 175 with the left-hand exhaust port 174 so that compressed air is supplied to the head end of the motor 80 to operate the piston rod 79 toward the left. This is the working stroke of the motor which advances the stringer through the machine by one step. Thus, energizing of the solenoid 184 causes the machine to advance 50 the stringer.

Figure 12 shows a wiring diagram for the machine. Before explaining the circuits in Figure 12 reference should be made to Figure 8 which shows the feed motor 80, the vertical clamping motor 128 and the horizontal clamping motor 138. There is only one feed motor 80, but there are two vertical clamping motors 128 and two horizontal clamping motors 138. Both of the latter are shown in Figure 5 projecting beyond the back of the machine, and the vertical clamping motors 128 are indicated in dotted lines ahead of the horizontal clamping motors in Figure 5. In the preferred construction, all of these motors have solenoid-operated valves for admitting compressed air to their cylinders, and the solenoids are preferably controlled by relay switches; but, for purposes of simplifying the description, the relay coils in 60 Figure 12 will be considered to be the solenoids which operate the valves.

The location of the coils in Figure 12 corresponds in orientation to the location of the fluid motors in Figure 5. For example a coil 201 operates the valve that controls the right hand vertical clamping motor 128 and a coil 202 operates the valve that controls the vertical left-hand clamping motor 128. Another coil 204 operates the valve 70 that controls the right-hand horizontal clamping motor

138 and a coil 205 operates the valve that controls the left-hand horizontal clamping motor 138. The valve 166 which controls the feed motor 80, is operated by the solenoid coil 184, as previously explained.

5 The coils 201, 202, 204 and 205 have switches 211, 212, 214 and 215, respectively, associated with them. These switches are normally open, that is they have a bias toward open position and they are closed when the coils are energized. Each of the switches 211, 212, 214 and 215 is connected in the circuit of its respective coil in such a way as to provide a shunt circuit for maintaining the coil energized after it has been momentarily energized by operation of a controller 217.

There is a switch 220 associated with the coil 184. This switch 220 is somewhat different from the other switches in that it has a spring 222 for holding the movable blade of the switch 220 in whatever position it was last shifted to by energizing of the coil 184 or a companion coil 224 which pulls the switch blade back against a fixed stop 226 at a particular time in the operating cycle, as will be more fully explained in a later description of the operation of the circuit. Power is supplied to the switch 220 and the coil 184 from a transformer 230 which has its primary winding connected to a source of power indicated by the reference character 231.

Power for operating all of the other switches of the control mechanism is supplied from a separate transformer 235 which has its primary coil connected with a source of power indicated by the reference character 236. The circuit for one side of the secondary coil of the transformer 235 is through the frame of the machine, as indicated by the ground connection on the secondary coil of the transformer 235, and the ground connections on various other circuits of the wiring diagram. The other side of the transformer 235 is connected with a selector switch 240 having a movable blade 241 which contacts selectively with fixed contacts 244 and 245 on opposite sides of the switch 240. This switch 240 is operated by the handle 105 which reverses the direction of feed of the machine.

When the reverse control handle 105 is in position to cause the machine to feed a stringer in the direction which requires use of the right-hand guide plate 17 and the right-hand clamping motors 128 and 138, the movable switch blade 241 is in the position shown in full line in Figure 12 so that it closes a circuit, to the coils 201 and 204, which operate the valves for controlling the right-hand clamping motors 128 and 138.

The controller 217 has a contact arm 250 which rotates angularly about a center and progressively into contact with the contacts A, B, C, D and E, located at angularly spaced regions around the center of the controller 217. The contact arm 250 is connected by a conductor 251 to one side of the transformer 230, and is connected by a conductor 253 to the lead screw 88 which adjusts the feed stroke of the machine. When the extension 84 is in contact with the abutment 92 on the end of the lead screw 88, a circuit is completed from the contact arm 250, through the conductor 253 and lead screw 88, to the abutment 92 and then to the extension 85 which is grounded on the frame of the machine.

The abutment 92 is insulated from the lead screw 88 and the conductor 253 is connected with this abutment through an opening in the lead screw with insulation around the conductor 253 to prevent it from being grounded on the lead screw and the block 90 through which the lead screw threads. The purpose of this ground connection through the abutment 92 and extension 84 is to prevent any of the circuits, except the circuit which controls the feed motor 80, from being operated before the feed motor has completed its stroke and brought the extension 84 into contact with the abutment 92.

There is another coil 260 which operates a switch 262. This switch 262 is provided with a spring 263 which normally holds the switch 262 closed, and the switch is opened

when the coil 260 is energized, near the end of an operating cycle, for the purpose of releasing all of the shunt circuits of the clamp motor operating coils 201, 202, 204 and 205. The operation of the control mechanism shown in Figure 12 is as follows:

The operator first moves the contact arm 250 of the controller 217 into position to touch the contact A. This closes a circuit from the transformer 230 through the solenoid coil 184, through the conductor 265, contact A, contact arm 250 and through the conductor 251 back to the other side of the transformer 230. When the coil 184 is energized, it attracts the movable arm of the switch 220 to a contact 267 which is connected with the conductor 265. This establishes a shunt circuit from the conductor 265, through the switch 220 and through a conductor 269 back to the other side of the transformer 230. This shunt circuit maintains the coil 184 energized after the circuit through the contact arm 250 has been broken by moving the contact arm 250 beyond the contact A of the controller 217.

With the coil 184 thus energized, the valve 166 is operated to supply compressed air to the motor 80 which moves the stringer holder to advance the stringer for one step through the routing machine. At the end of the feed stroke of the motor 80, the extension 84 of the feed mechanism is in contact with the abutment 92 and is held in contact by the continued pressure of the working fluid in the feed motor 80. The operator next moves the contact arm 250 to the second contact B on the controller 217. This establishes a ground circuit for the coils 204 and 205 which operate the valves that control the horizontal clamping motors. However, only one of the coils 204 and 205 is energized, depending upon the position of the movable arm 241 of the selector switch 240. In the wiring diagram shown in Figure 12, the arm of the selector switch 240 is in contact with the fixed contact 245 and this establishes a circuit from the transformer 235, through the selector switch 240, fixed contact 245, coil 204 and through a conductor 271, contact B of the controller 217, contact arm 250, conductor 253, abutment 92, extension 84 and then through the frame of the machine back to the other side of the transformer 235.

This energizing of the coil 204 operates the valve to supply compressed air to the right hand clamping motor 138, and at the same time moves the switch arm 214 into position to touch a contact 272 and establish a circuit through a conductor 273 to a fixed contact 275 in the switch 262 which is grounded on the frame. This shunt circuit keeps the coil 204 energized after the contact arm 250 is moved beyond the contact B of the controller 217.

The operator then moves the contact arm 250 to the third contact C and this establishes a circuit from the transformer 235, through the switch 240, fixed contact 245, a conductor 277, coil 201, conductor 279, contact C, contact arm 250 and thence through the conductor 253 to the frame of the machine as previously explained. This energizing of the coil 201 moves the arm 211 into position to touch a fixed contact at the end of a conductor 280 which establishes a shunt circuit through the switch 262 for maintaining the coil 202 energized after the contact arm 250 has been moved beyond the contact C of the controller 217.

The energizing of the coil 201 operates the valve which controls the vertical right-hand clamping motor 128. The feed motor and both of the right-hand clamping motors are now operated by compressed air and the parts of the machine are in position to perform the routing step on the stringer. After the routing step has been completed, the operator moves the contact arm 250 into position to touch the contact D of the controller 217. This energizes the coil 224 through a conductor 282 which is always connected with the transformer 235 regardless of the position of the selector switch 240. The coil 224 is grounded through the contact D and the contact arm 250 to the con-

ductor 253 which connects with the frame of the machine as previously described.

Energizing of the coil 224 pulls the blade of the switch 220 away from the coil 184 and into contact with the fixed abutment 226. This opens the circuit of the coil 184 and permits the valve 166 to return to its original position under pressure of the spring in the valve 166 as previously described. The direction of flow of working fluid to the feed motor 80 is reversed and the motor returns to its original position in preparation for another feed stroke.

The next step in the operation of the machine is to de-energize the coils 201 and 204 so that the valves which are operated by these coils will return to their normal positions, under influence of spring bias of the valve, and the clamps are thus released. This is accomplished by moving the contact arm 250 to position to touch the contact E of the controller 217. With the contact arm 250 on the contact E a circuit is closed from the transformer 230, through conductor 286, coil 260, conductor 287, contact E, contact arm 250, and back through the conductor 251 to the other side of the transformer 230. This energizing of the coil 260 opens the switch 262 and breaks the ground connection of both of the coils 201 and 204 so that their switches 211 and 214 move into open position and leave the circuits of these coils 201 and 204 open even after the switch 262 closes again when the arm 250 is moved to the bottom, off position shown in Figure 12.

The preferred embodiment of this invention has been illustrated and described, but changes and modifications can be made and some features can be used alone or in different combinations without departing from the invention as defined in the claims.

I claim as my invention:

1. A machine for routing stair stringers including a fixed frame, a stringer carrier movable through the fixed frame, a router guideplate having two intersecting guide slots therein corresponding to the riser and tread of the stairs, the guideplate being located on the frame above the stringer carrier, bearing means by which the guideplate is attached to the frame at a relatively fixed location on said frame and about which the guideplate is rotatable about a center near the intersection of the guide slots in the plate to change the ratio of rise to run for the stringers routed by the machine, feed mechanism for advancing the stringer carrier with a step-by-step movement past the guideplate, and adjustable means for changing the length of the steps of the feed mechanism in accordance with the position of the guideplate to adjust the machine for stair stringers having different ratios of rise to run.

2. A stair stringer routing machine comprising a fixed frame, a stringer carrier extending through the fixed frame and movable longitudinally with respect to the fixed frame, reversible mechanism for feeding the stringer carrier in opposite directions with a step-by-step movement, two guideplates supported by the frame and located above the stringer carrier, the guideplates having slots therein through which a router extends with a side of each guide slot serving as a guide for controlling the path followed by the router, each of the plates having two intersecting guide slots, one for the riser channel and the other for the tread channel of the stringers, and one of the plates having the guide slots in position for a right-hand stringer while the other guideplate has the slots in position for a corresponding left-hand stringer, bearing means on which the guideplates are movable to change the angular positions of the guide slots with respect to the longitudinal edges of a stringer on the carrier to change the ratio of the rise and run of the channels routed by the machine, and means for adjusting the feed mechanism to accommodate the rise-run ratio for which the guideplates are adjusted.

3. A stair stringer routing machine including a fixed frame, a stringer carrier movable lengthwise through the fixed frame, a guideplate supported by the frame and

having intersecting slots for guiding a router which cuts a channel for the riser and a channel for the tread, both of the guide slots extending beyond one margin of a stringer supported on the carrier, bearing means on which

5 the plate is rotatable to change the ratio of the riser channel length to the tread channel length, an adjusting screw for rotating the plate on the bearing means, a scale and indicator, one of which is on the plate and the other on the frame, for measuring the angular position of the plate, feed mechanism that advances the carrier with a step-by-step movement, and means for adjusting the feed mechanism to co-ordinate the length of each step with the angular adjustment of the guideplate.

4. The stair stringer routing machine described in claim 15 3 and in which the feed mechanism includes a reciprocating fluid motor and motion-transmitting connections between the fluid motor and the stringer carrier for imparting the step-by-step movement to the stringer carrier.

5. The stair stringer routing machine described in claim 20 3 and in which the feed mechanism includes a reciprocating fluid motor, and motion-transmitting connections between the motor and the stringer carrier, said connections including a rack operated by the fluid motor, a pinion that meshes with the rack, another rack carried by the stringer 25 carrier, a pinion that meshes with the stringer carrier rack, and gearing between the pinions including means for reversing the direction of rotation of one pinion with respect to the other when the stringer carrier is to be fed in an opposite direction.

30 6. A stair stringer routing machine including a frame, a stringer carrier movable lengthwise with respect to the frame, a plate supported by the frame and having a plurality of guide slots therethrough for guiding a routing tool, the guide slots being correlated for producing a

35 riser channel and a tread channel for a right-hand stringer, another guideplate supported by the frame and having slots therein for guiding a router tool to produce a riser channel and a tread channel for a left-hand stringer, the guide slots extending beyond one edge of the stringer on the carrier, bearing means on which each of the guideplates is movable to change the angles of the guide slots with respect to the edge of the stringer to change the rise-run ratio of the stringer, common adjustment means connected with both of the guideplates for adjusting the

40 plates in unison, indicators for designating the angular positions of the guideplates, feed mechanism that produces step-by-step relative movement of the stringer carrier and frame, and means for adjusting the feed mechanism to change the length of the steps in accordance with the angular setting of the guideplates.

7. A stair stringer routing machine including a frame, a stair stringer holder, step-by-step feed mechanism for producing relative movement of the holder and frame, a plate supported by the frame above the stringer and having router guide slots therein including one for a riser channel and another for a tread channel, a clamping face beneath the plate and above a stringer on said holder, a clamping jaw beneath the stringer, operating mechanism that moves the clamping jaw toward the level of the

60 clamping face to clamp the stringer against said clamping face prior to each routing operation, said operating mechanism being movable into position to release the clamping pressure prior to the operation of the feed mechanism after each routing operation, and bearing means on which the plate is rotatable to change the ratio of the riser channel length to the tread channel length.

8. A stair stringer routing machine including a main frame, a stringer holder, feed mechanism that advances the stringer holder in a direction longitudinally of the frame and past a router station on the main frame with a step-by-step movement, a guideplate connected to the frame at the router station and supported by said frame at a location above the stringer, guide slots in the plate at substantially right angles to one another for extending beyond one longitudinal edge of the stringer on the

holder, bearing means on which the guideplate is rotatable with respect to the frame to change the rise-run ratio of the stringer, a clamping face on the frame, and clamping means carried by the frame in position to exert a clamping pressure against the stringer in a direction transverse of the stringer and toward said clamping face to clamp the stringer against said face prior to each routing operation, and control means operable to release the clamping means prior to each operation of the step-by-step feed mechanism at a location near the slots in the plate.

9. The stair stringer routing machine described in claim 8, and in which there are other clamping means located beneath the stringer and operable to thrust the stringer upwardly against a face of the frame.

10. A stair stringer routing machine including a frame, a stringer holder, feed means that produce relative step-by-step movement of the stringer holder and frame in a direction longitudinally of the holder, two guideplates supported by the frame and connected with bearing means on which the guideplates are movable into different angular positions in a plane parallel to the stringer face in which channels are to be routed, guide slots in the plates for guiding a router tool to cut channels in the stringers, the guide slots in one plate being correlated for a right-hand stringer and the guide slots in the other plate being correlated for a left-hand stringer, clamping means for holding a stringer in position during a routing operation, the clamping means including separate power clamps for each of the guideplates, a controller for the clamps, and selector mechanism alternately connecting one or the other of the clamps with the controller.

11. A stair stringer routing machine including a frame, a stringer holder, feed mechanism that produces step-by-

step relative motion of the stringer holder and frame in a direction lengthwise of the frame, a guideplate carried by the frame with slots therein for guiding a router tool to cut a riser channel and a tread channel in a face of the stringer, bearing means on which the plate is movable to change the angular positions of the riser and tread channels with respect to a longitudinal edge of the stringer to change the rise-run ratio of the stringer, clamping means for holding the stringer in position during a routing operation, said clamping means including a horizontally actuated and a vertically actuated clamp and faces on the frame confronting the clamps and against which the stringer is held by the clamps at locations in the region of the guide slots, power actuating means for the clamps, a controller, and switch means operated by the controller for controlling the actuating means of the clamps.

12. The stair stringer routing machine described in claim 11 and in which the power actuating means include reciprocating fluid motors, and in which the feed mechanism includes a reciprocating fluid motor, and the controller has a group of separate switches which are successively operated to supply working fluid to the feed motor first and then to the clamping motors.
